STATION ANNOUNCER

Pauline Smith, Williamson, W. Va.

Application October 5, 1936, Serial No. 104,117

2 Claims. (Cl. 40—31)

This invention relates to devices for use on trains, electric cars and analogous vehicles for conveyance in apprising the passengers of the next "station" or "stop"; and an object of the present invention is to, generally, improve upon devices of this general character as now known and/or used.

The invention together with its objects and advantages will be best understood from a study 10 of the following description taken in connection with the accompanying drawings wherein:—

Figure 1 is a front elevational view of the device.

Figure 2 is a side elevational view thereof.

Figure 3 is a sectional view taken substantially 15 on the line 3—3 of Figure 2.

Figure 4 is an elevational view of a reflector.

Figure 5 is a wiring diagram.

Figure 6 is a side elevational view of a slightly 20 modified form of the invention.

Figure 7 is a fragmentary elevational view taken substantially at right angles to Figure 6.

In carrying the invention into practice there 25 is first provided in a wall or analogous partition 6 of a train coach, electric car or the like, a pair of vertically spaced upper and lower elongated openings 7 and 8 respectively. Over the openings 7 and 8 are placed transparencies 9 and 10 respectively. The transparencies 9 and 10 which 30 may be of clear or colored glass, as found desirable, are secured in position through the medium of a suitable frame 11 that in turn is secured to the partition 6 through the medium of suitable fastening elements 12.

Suitably confined behind the glass 9 is a stencil 13 suitably provided, in the present instance, with the legend "This train is approaching".

For illuminating the stencil 13 there are provided behind the stencil 13 a plurality, in the 40 present instance three electric lamp bulbs 14 that are arranged in circuit with a battery B and the lamp circuit 14 is provided with a manually operable switch 15.

The lamps 14 are accommodated in suitable 45 electric sockets 16 suitably mounted on and supported through the medium of an elongated substantially semi-cylindrical reflector 17 that has the open side thereof fitting snugly within the opening 7 in the partition 6 as shown in Figure 50 3. It will thus be seen that when switch 15 is closed the circuit will be completed through the lamps 14 for illuminating the sign 13.

Suitably secured within the opening 8 is an 55 elongated frame 18 the upper and lower sides of which merge into angularly disposed guide

flanges or platens 19. The platens 19 respectively, at the respective opposite ends thereof are provided with flange 20 through the medium of which and fastening elements 21 the frame 18 is secured in position on the partition 6 and with- 5 in a housing or casing 22.

The housing or casing 22 is mounted behind the partition 6 and at the side thereof disposed against the partition 6 is provided with a continuous flange through the medium of which 10 and suitable fastening elements 23 the housing 22 is secured in position on the partition.

At the side thereof farthest from the partition the frame 18 is provided with a continuous spring lip 23 and at the junction of the frame 18 and 15 20 the lip 23 there is provided a continuous internal groove 24 which receives the beaded edge of a reflector 25 whereby the reflector 25 is removably supported in position rearwardly of the transparency or glass 10.

Suitably mounted and supported by the reflector 25 are a plurality, in the present instance three electric lamp sockets 26 which accommodate electric lamps 27.

The lamps 27 are also arranged in circuit with 25 the battery B and the circuit for the lamps 27 is provided with a manually operable control switch 28.

A removable back 29 is suitably provided for the casing 22. Thus access may be had to the 30 casing for purposes desirable.

Suitably journaled in the casing 22 are upper and lower rolls or reels 30, 31 on which are windable the respective opposite ends of a web 32.

The web 32 at intervals is provided with the 35 name of "stations" or "stops" along the route of the vehicle as indicated generally at 33. Thus it will be seen that when a legend such as the name of a town or the like 33 on the web 32 40 is positioned opposite to and directly behind the glass 10 and switch 28 is closed, the said section of the web will be illuminated so that the legend thereon will be clearly discernible and visible.

As clearly shown in Figure 2 the reels or rolls 45 30, 31 are provided at their respective opposite ends with pintles suitably journaled in the side walls of the casing 22 and the pintles at one end of the rolls or reels 30, 31 are flexed or otherwise provided as indicated generally at 34 to accommodate a handle or crank 35. Thus it will be seen that with the crank 35 engaged with the pintle 34 of roll or reel 30 the latter may be turned for winding the web 32 on said reel 30 50 while when the crank 35 is engaged with the 55

pintle 34 of the reel 31 the latter may be turned for winding the web 32 on said reel.

- The section of the frame 11 in which is confined the transparency 10 is provided at its respective opposite ends with bull's-eyes 36 behind which are suitable mounted electric lamps 37 also arranged in circuit with the battery B. The circuit for the lamps 37 is provided with a manually operable switch 38. Obviously, when the switch 38 is closed the circuit will be completed through the lamps 37 to provide intermittent illumination at the respective opposite ends at the lower section of frame 11, the lamps 37 when illuminated thus serving as a means for attracting the attention of the passengers of the vehicle to the "station announcer". Lamps 37 may be either of the "flasher" type or flasher mechanisms may be arranged in circuit with said lamps.
- 20 It will be seen that the flanges 19 of the frame 13 serve as guide means for the web 32 and serve to maintain the web 32 taut and to facilitate the winding of the web on the selected roll or reel 30, 31.
- 25 In actual practice it is contemplated that, for example, five minutes in advance of the time at which the train or vehicle will reach the next station, the conductor or other attendant will adjust the web 32 so that the name of the "station" or "stop" now being approached by the train will be brought to view opposite the transparency or glass 10. After this has been accomplished the switches 15, 23 and 38 are closed for illuminating the device with the result that the occupants of the vehicle will have their attention called to the device and through the medium of the device be apprised as to the name of the station or town at which the next stop will be made.
- 40 Obviously, on the first trip the web 32 will be wound, for example, on the reel or roller 30 while on the return trip the web 32 will be wound on the reel or roll 31.
- 45 In Figures 6 and 7 there is illustrated a slightly modified form of the invention, and in this form of the invention instead of having the device manually operated the same may be run from an electric motor such as for example a reversible electric motor indicated generally by the reference numeral 39. Thus in this second form of the invention, which will otherwise be somewhat similar to the form of the invention shown in Figures 1 to 5 inclusive, there are suitably mounted adjacent the reels 30', 31' rollers 40 and 41 respectively. Also, in this form of the invention, the rolls or reels 30', 31' are supported between pairs of arms 42 which are pivoted at one end as at 43. Spring devices 44 suitably anchored at one end as at 45 and connected with the arms 42 as at 46 serve to bias the respective rolls or reels 30', 31' toward the respective rollers 40, 41 so as to maintain the web portions wound on the reels or rolls in frictional contact with the periphery of the rollers 40, 41. In this connection it will be noted that preferably the peripheries of the rollers 40, 41 are roughened or otherwise formed to have good friction bearing surface with the web 32'.
- 70 The rollers 40, 41 are provided at one end with pulleys 46, 47 while the armature shaft of the motor 39 is provided with a pulley 48. Trained over the pulley 48 is an endless belt 49 which is adapted to be trained over the pulley 46 of roller 40 when it is desired to wind the web 32 on the

roll 30' and over the pulley 47 when it is desired to wind the web 32' on the roll 31'.

The spacing of the legends, that is to say the names of the several towns or stops appearing on the web 32 will be relatively spaced apart a distance corresponding to one-half revolution of a disk 48 mounted, in the present instance, on one end of the shaft of the upper roller 40.

At diametrically opposite points thereon the disk 48 is provided with slots 50, 51 cooperable with a slidably mounted latch rod 52 suitably mounted as shown in Figure 7 whereby to limit successive rotations of the disk 48 to half revolutions.

A suitable spring device 53 is provided for normally urging one end of the rod 52 into wiping engagement with a side of the disk 48 and to project said end of the rod 52 into a slot 50, 51 as such slot moves into alignment with said end of the rod 52.

For closing the circuit through the motor 39 there is provided a suitably mounted switch which includes a spring contact 54 and a spring contact 55, the free ends of which contacts are arranged in the path of a fixed collar 56 on the rod 52 as shown in Figure 7.

Thus it will be seen that in this form of the invention when, for example, it is desired to wind the web 32' onto the roll 30' to bring the next station legend on the web 32' opposite the window 10 the operator pulls on the rod 52 against the action of spring 53. This will result in the withdrawal of the end of the rod 52 out of, for example, the slot 50. At the same time collar 56 will engage contact 55 and move the same into engagement with the contact 54 for completing the circuit through the motor 39. Drive will then be transmitted from the motor 39 to the roller 40 and through the roller 40 and web 32' to the roll 30' for winding the web 32' onto the roll 30'. At about the time the proper station legend on the web 32' moves opposite the sight window 10 slot 51 will have moved into a position of alignment with the rod 52 with the result that the latter in response to the action of spring 53 will be forced through the slot 51 for arresting further movement of the disk 48 and consequently of the web 32'.

For bringing each successive station legend on the web 32' into visible position opposite the window 10 the operation just described is repeated.

In connection with the above it will be appreciated that as the rod 52 in response to the action of spring 53 is projected into a slot 50, or 51 as the case may be, contacts 54 and 55 will spread apart thus interrupting the circuit through the motor 39 so that drive from the motor to the roller 40, or 41 as the case may be, will cease and consequently the winding of the web 32' will stop at about the time when the proper legend on the web moves opposite the window 10.

It is thought that a clear understanding of the construction, utility and advantages of an invention of this character will be had without a more detailed description.

Having thus described the invention what is claimed as new is:—

1. In a station-announcer, a partition provided with a pair of spaced upper and lower openings, a casing mounted on the partition opposite said openings and at one side of the partition, a frame mounted on the partition at the side thereof opposite to the casing and having sections bordering the respective openings, transparencies mounted in the sections of the frame and substantially

5 closing the respective openings, a legend-bearing stencil disposed behind the transparency closing the upper opening, upper and lower rollers journaled in the casing, a legend-carrying and display web arranged to wind upon the rollers, for presenting the legends thereon successively opposite the transparency closing the lower one of said openings, and means for rotating either roller to move the web in one or the other direction,
10 10 said means including a reversible electric motor, stop means for arresting the rotative movement of the roll when a legend on the webbing moves into position opposite the lower opening, a control switch for said motor, and said stop means including manually operated releasing means for simultaneously actuating said switch to close the latter upon release of the stop means.

2. In a station-announcer, a partition provided with a pair of spaced upper and lower openings,
20 20 a casing mounted on the partition opposite said openings and at one side of the partition, a frame mounted on the partition at the side thereof opposite to the casing and having sections bordering the respective openings, transparencies

5 mounted in the sections of the frame and substantially closing the respective openings, a legend-bearing stencil disposed behind the transparency closing the upper openings, upper and lower rollers journaled in the casing, a legend-carrying and display web arranged to wind upon the rollers, for presenting the legends thereon successively opposite the transparency closing the lower one of said openings, and means for rotating either roller to move the web in one or the other direction, said means including a reversible electric motor, stop means for arresting the rotative movement of the roll when a legend on the webbing moves into position opposite the lower opening, a control switch for said motor, said stop means including a rotatable disk having openings therein, a manually retractable spring projected plunger operable to enter said openings to secure the disk against rotation and a projection on the plunger movable into engagement with the switch to close the same upon releasing movement of the plunger.
